SPINDLE SUPPORTING APPARATUS

Richard W. Young, Worcester, Mass., assignor to
 Morgan Construction Company, Worcester,
 Mass., a corporation of Massachusetts

Application October 30, 1942, Serial No. 463,985

8 Claims. (Cl. 80—31.1)

This invention relates to spindle supporting apparatus, and more particularly to apparatus for supporting the universal coupling spindles of a rolling mill in order to facilitate the changing of the rolls.

The ordinary rolling mill used in the production of metal bars, rods and the like comprises a pair of horizontal rolls which are connected to pinion shafts by means of universal coupling spindles. These spindles serve to drive the rolls without interfering with vertical adjustments of the rolls to control the size of the product. When a roll is changed it is necessary to support the weight of the corresponding spindle. The use of an overhead crane for this purpose is common but undesirable, since such use ties up some very expensive equipment which is usually needed for other purposes. While various forms of jacks and the like have been proposed, they have been for the most part expensive, complicated, and comparatively inconvenient to operate.

It is accordingly one object of the invention to provide a comparatively simple and inexpensive spindle supporting apparatus which can be controlled in a very convenient manner.

It is a further object of the invention to provide a rugged and dependable apparatus which will support either or both of the two coupling spindles of a rolling mill.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is an elevation of a spindle supporting apparatus;

Fig. 2 is a section through the apparatus, taken on the line 2—2 of Fig. 3;

Fig. 3 is a section taken on the line 3—3 of Fig. 2;

Fig. 4 is an elevation of the apparatus as viewed from the right hand side of Fig. 1;

Fig. 5 is a fragmentary sectional view, similar to a portion of Fig. 2, but showing one of the parts in a different position of adjustment; and

Fig. 6 is a side elevation of the apparatus installed adjacent to a rolling mill.

In Fig. 6 there is shown a rolling mill comprising a roll housing 10 which provides a support for a pair of horizontal rolls 11 having roll necks 12. A pair of pinion shafts 14 are arranged in approximate alignment with the rolls,

these shafts extending from a pinion housing 15 to provide a driving means for the rolls. The pinion shafts are connected to the roll necks by means of universal coupling spindles 16 including the usual coupling sleeves 17, one satisfactory construction being disclosed in the patent to Morgan No. 2,136,947. The weight of coupling spindles is normally carried by the roll necks 12 and the pinion shafts 14, but when the rolls are removed for replacement it becomes necessary to support the adjacent ends of the spindles by other means. The present invention is concerned with the construction of apparatus for this purpose.

15 The embodiment of the invention illustrated comprises a frame 19 in the form of an upwardly open box having a bottom wall 20 and two parallel upright side walls 21. As shown in Fig. 2, the side walls are connected by two upright plates 23 which extend part way down from the tops of the side walls and by two upright plates 24 which extend part way up from the bottom wall 20 near the ends thereof. The plates 23 are located somewhat closer together than the plates 24. The side walls 21 are provided with U-shaped notches 25 (Fig. 1) of sufficient size to avoid interference with the sleeve 17 of the lower coupling spindle when the frame 19 is mounted beneath this sleeve and adjacent the roll housing 10 as shown in Fig. 6.

20 Within the frame 19 there is provided a vertically slidable carriage 26 in the form of an upwardly open box having a bottom wall 27, two parallel upright side walls 28, and two parallel upright end walls 29. The side walls 28 are provided with U-shaped notches 30 of sufficient size to avoid interference with the sleeve 17 of the lower coupling spindle. The end walls 29 are provided with bosses 31 having convex outer faces for engagement with the inner surfaces of the adjacent plates 23. Lugs 32 project from the upper portions of the end walls 29 over the tops of the plates 23 to limit the downward travel of the carriage. Bosses 33 extend inwardly from the inner surfaces of the side walls 21 of the frame for engagement with the outer surfaces of the side walls 28. These side walls 28 extend downwardly below the bottom wall 27, and between these downwardly extending portions 25 there is provided a horizontal lever 35 which is fulcrumed at the end on a pin 36 supported by the side walls 21 of the frame. The other end of the lever is connected to the piston rod 38 of a fluid motor comprising a vertical cylinder 39 having a slidable piston 40 therein. The cylin-

der is pivotally supported between the side walls 21 by means of trunnions 42. The movements of the piston are controlled by a four-way valve 43 mounted on a shelf 44 projecting from one of the side walls 21. This valve is supplied with pressure fluid from any suitable source, and it is connected to the opposite ends of the cylinder 39 by means of tubes 45 which are sufficiently flexible to permit a slight oscillation of the cylinder in its trunnion bearings as the piston moves. The valve 43 can be actuated manually by means of an operating handle 46. On the center of the bottom wall 21 there is provided a lug 48 which projects downwardly into a socket 49 in the upper surface of the lever 35. It will be clear that with this construction the lever 35 and the carriage 26 may be raised and lowered as desired merely by manipulating the handle 46.

The carriage is provided with means adapted to engage either or both of the adjacent coupling sleeves 17 to support the same during roll changes. For this purpose an upper pair and a lower pair of dogs or arms 51 are pivotally supported between the side walls 28 of the carriage by means of pins 52 each of which is provided at one end with a handle 53. As shown in Fig. 1, one of the side walls 21 of the frame 19 is formed with two openings 54 through which the two lower pins 52 extend. On the upper end of each arm 51 there are mounted two idler rollers 56 for contact with the adjacent coupling sleeves 17. The lower end of each arm 51 is shaped as a lug 57 which engages an abutment 58 on the carriage to limit the downward movement of the arm and hold it in its operative position. Additional abutments 59 are provided on the carriage to support the arms when they are raised to inoperative positions, as indicated in Fig. 5, the center of gravity of each arm being then located outwardly of its pivotal axis so that the arm will remain in the desired position until moved by means of the corresponding handle.

The operation of the invention will now be apparent from the above disclosure. Normally the lugs 32 will rest upon the upper edges of the plates 23, thereby supporting the carriage 26 in its lowermost position, with the rollers 56 out of contact with the coupling sleeves 17. When one of the mill rolls 11 needs changing, the corresponding pair of arms 51 will be swung inwardly beneath the adjacent sleeve 17. The operator will then manipulate the pilot valve handle 46 to admit pressure fluid into the lower end of the cylinder 39. This will cause the piston 40 to move upwardly, lifting the lever 35 and the carriage 26 until the rollers 56 on the inwardly positioned arms 51 engage the sleeve 17 and lift the same sufficiently to remove the weight of the coupling spindle from the roll neck. The operator will then return the pilot valve to neutral position and stop the movement of the carriage, whereupon the roll can be changed and the carriage thereafter lowered to its original position. Obviously if only one of the rolls is to be changed, it is necessary to lift only the corresponding coupling spindle, and this can readily be done with the apparatus disclosed. If by chance a careless operator should start rotation of the spindles while one of them is supported by the corresponding arms 51, the rollers 56 will turn and the spindle will remain supported in the proper position. The apparatus is comparatively simple and inexpensive to manufacture, and convenient to operate.

Having thus described my invention, what I

claim as new and desire to secure by Letters Patent is:

1. In combination with a rolling mill having an upper roll, a lower roll, and a pair of substantially horizontal coupling spindles to drive the rolls, a frame located beneath the spindles, a carriage movable vertically in the frame, means to raise and lower the carriage, separate devices on the carriage to engage the respective spindles and support the same while the rolls are being changed, and means to retract the said devices independently to inoperative positions.

2. In combination with a rolling mill having a roll and a substantially horizontal coupling spindle to drive the same, a frame located beneath the spindle, a carriage movable vertically in the frame, means to raise and lower the carriage, a pair of dogs pivotally mounted on the carriage and arranged to support the spindle when the carriage is raised, and means to swing the dogs about their pivots to inoperative positions.

3. In combination with a rolling mill having an upper roll, a lower roll, and a pair of substantially horizontal coupling spindles to drive the rolls, a frame located beneath the spindles, a carriage movable vertically in the frame, means to raise and lower the carriage, an upper pair of dogs and a lower pair of dogs pivotally mounted on the carriage adjacent the respective spindles and arranged to support the same when the carriage is raised, and means to swing the dogs about their pivots to inoperative positions.

4. In combination with a rolling mill having a roll and a substantially horizontal coupling spindle to drive the same, a frame located beneath the spindle, a carriage movable vertically in the frame, means to raise and lower the carriage, a pair of arms pivotally mounted on the carriage, idler rollers mounted on the ends of the arms and arranged to engage the spindle and to support the same when the carriage is raised, and means to swing the arms about their pivots to inoperative positions.

5. In combination with a rolling mill having an upper roll, a lower roll, and a pair of substantially horizontal coupling spindles to drive the rolls, a frame located beneath the spindles, a carriage movable vertically in the frame, means to raise and lower the carriage, an upper pair of arms and a lower pair of arms pivotally mounted on the carriage adjacent the respective spindles, idler rollers mounted on the ends of the arms and arranged to engage the spindles and to support the same when the carriage is raised, and means to swing the arms about their pivots to inoperative positions.

6. In combination with a rolling mill having a roll and a substantially horizontal coupling spindle to drive the same, a frame located beneath the spindle, a carriage movable vertically in the frame, means on the carriage to engage the spindle and support the same when the carriage is raised, a substantially horizontal lever beneath the carriage in supporting relation thereto, and means to actuate the lever to raise and lower the carriage.

7. In combination with a rolling mill having a roll and a substantially horizontal coupling spindle to drive the same, a frame located beneath the spindle, a carriage movable vertically in the frame, means on the carriage to engage the spindle and support the same when the carriage is raised, a substantially horizontal lever beneath the carriage in supporting relation thereto, means on the frame providing a fulcrum for the lever

at one end thereof, and a fluid motor mounted on the frame above the other end of the lever and connected thereto to raise and lower the same.

8. In combination with a rolling mill having a roll and a substantially horizontal coupling spindle to drive the same, a frame located beneath the spindle and shaped as an upwardly open box having two upright side walls which are notched to avoid interference with the spin-

5 dle, a carriage movable vertically within the box and likewise shaped as an upwardly open box having two upright side walls which are notched to avoid interference with the spindle, a pair of dogs pivotally mounted on the carriage and arranged to support the spindle when the carriage is raised, and means to swing the dogs about their pivots to inoperative positions.

RICHARD W. YOUNG.

CERTIFICATE OF CORRECTION.

Patent No. 2,363,378.

November 21, 1944.

RICHARD W. YOUNG.

It is hereby certified that error appears in the printed specification of the above numbered patent requiring correction as follows: Page 1, second column, line 51, for "the end" read --one end--; page 2, second column, line 55, claim 5, for "in" read --to--; and that the said Letters Patent should be read with this correction therein that the same may conform to the record of the case in the Patent Office.

Signed and sealed this 13th day of February, A. D. 1945.

Leslie Frazer
